W. PRELLWITZ

WATER TUBE BACK HEAD CONNECTION FOR ROCK DRILLS

Filed March 21, 1924

UNITED STATES PATENT OFFICE.

WILLIAM PRELLWITZ, OF EASTON, PENNSYLVANIA, ASSIGNOR TO INGERSOLL-RAND COMPANY, OF JERSEY CITY, NEW JERSEY, A CORPORATION OF NEW JERSEY.

WATER-TUBE BACK-HEAD CONNECTION FOR ROCK DRILLS.

Application filed March 21, 1924. Serial No. 700,789.

To all whom it may concern:

Be it known that I, WILLIAM PRELLWITZ, a citizen of the United States, and a resident of Easton, county of Northampton, and

5 State of Pennsylvania, have invented a certain Water-Tube Back-Head Connection for Rock Drills, of which the following is a specification accompanied by drawings.

This invention relates to rock drills of the hammer type, but more particularly to an improved connection between the liquid conducting tube and the back head of the rock drill, including an improved means for removing the liquid conducting tube in the 15 event of breakage thereto or for any other reason.

Most rock drills of the hammer type employ a tube which extends through the machine and a short distance into the drill steel 20 for conveying liquid under pressure to the hollow bore of the drill steel for the purpose of cleansing the drilled hole. These tubes frequently becomes so damaged that they are of no further use which necessitates the 25 removal of the old tube and the substitution of a new tube. Heretofore, much trouble and annoyance has been occasioned in the removal of the damaged tubes and usually special tools are required for this operation.

30 It has also been a difficult problem to obtain an efficient fluid tight connection between the liquid conducting tube and the back head and frequently the liquid (usually water) enters the working parts 35 of the machine and washes away the lubricant. This, of course, is disadvantageous and tends to shorten the life of the machine.

By means of this invention the above difficulties are overcome and an efficient and reliable fluid tight connection is obtained between the liquid conducting tube and the back head of the machine and by means of a stem, which is readily accessible, the 45 liquid conducting tube and associated parts may be conveniently removed from the back head of the machine. Another feature of this invention resides in the provision of a vise formed on the machine which is adapted to receive a sleeve secured to the liquid conducting tube to enable the sleeve and tube to be separated from the back head plug so that a new tube may be substituted therefor, thereby eliminating the necessity 55 of special tools.

One object of this invention is to enable a liquid conducting tube to be secured to a back end portion of a rock drill in a simple and improved manner so that an efficient fluid tight connection therebetween 60 is produced.

Another object of this invention is to enable the liquid conducting tube of a rock drill to be readily removed without the use of special tools. 65

A further object of the invention is to provide means on the rock drill which will enable the liquid conducting tube to be separated from the back head plug without the necessity of special tools. 70

Further objects of the invention will hereinafter appear and the invention consists in certain features of a construction and combination of elements described in the following specification, defined in the appended claims and shown in the accompanying drawings, in which 75

Figure 1 is a side elevation partly in vertical section of a rock drill of the hammer type, 80

Figure 2 is an enlarged detailed vertical section of the connection between the liquid conducting tube and the back head shown in Figure 1, 85

Figure 3 is a transverse section taken on the line 3-3 of Figure 2 looking in the direction of the arrows, 90

Figure 4 is a perspective view of a portion of the back head showing the means for removing the liquid conducting tube from the back head plug, 95

Figure 5 is a sectional elevation showing the invention applied to a rock drill of the drifter type, and 100

Figure 6 is a sectional elevation showing a modified form of a water tube connection. 105

Referring to the drawings, the invention is shown embodied in a rock drill of the "jackhammer" type having a cylinder A to which is connected the front head B by suitable side bolts (not shown). A chuck C is located in the front head B and is adapted to receive the drill steel D for receiving the impact blows of the hammer piston E. A front cylinder bushing F preferably separates the cylinder A from the front head B and in this instance a valve chest G is connected to the cylinder A. Motive fluid is supplied to the rock drill through the inlet H and a suitable distributing valve is lo- 110

cated in the valve chest G for distributing the motive fluid to the hammer piston E.

A back head J is separated from the cylinder A by the ratchet ring K and the rifle bar head L is located inside the ratchet ring K. Suitable pawls (not shown) are carried by the rifle bar head L and cooperate with the ratchet ring K for enabling the rifle bar O to rotate in one direction but preventing 10 rotation in the opposite direction. Suitable washers P are in this instance located on the opposite ends of the rifle bar head L. The rifle bar O extends into the rifle nut Q carried by the piston E and as the piston E 15 reciprocates in the cylinder A, rotation is transmitted to the drill steel D by means of the chuck C and rifle bar O.

In this instance the back head J is formed with a tubular extension R on which is 20 slidably mounted a sleeve S carried by the handle T. A coil spring U is in this instance mounted in the extension R and bears at one end against the inwardly extending flange V in the handle T and the other end 25 bears against the bottom of the extension R. In this manner the jars and shocks set up in the operation of the tool will be absorbed by the coil spring U and not transmitted to the operator who grasps the handle T. 30 However the arrangement of the above mentioned cushion handle forms a subject matter of my application for patent, Serial No. 662,036; filed, September 11, 1923, and further description here is deemed unnecessary.

35 In accordance with this invention a sleeve W is preferably secured to the liquid conducting tube X in any suitable manner. The liquid conducting tube in this instance extends through the rifle bar head L, rifle bar O, piston E, and a short distance into the hollow bore of the drill steel D and is for the purpose of conveying liquid, such as water, into the drill steel D for cleansing the drilled hole of the cuttings. The sleeve 40 W is preferably formed with a threaded end portion Y which is adapted to be screwed into the recess Z formed in a back head plug a.

45 A tapered portion b is formed on the sleeve W and is adapted to cooperate with a tapered seat c formed in the back head plug a for forming a fluid tight connection between the sleeve W and the back head plug a. The back head plug a is in this instance formed with a tapered portion d which is 50 adapted to cooperate with a tapered seat e formed in the back head J for forming a fluid tight connection between the back head plug a and the back head J. An annular groove f is in this instance formed in the 55 tapered portion d of the back head plug a and communicates with the recess Z by means of a passage g.

60 The back head J is preferably formed 65 with an inlet opening h which is adapted to

communicate with the annular groove f in the back head plug a by means of a passage j formed in the back head J. Liquid under pressure is adapted to be introduced into the machine through the inlet opening h and 70 passes through the passage j, annular groove f, passage g, recess Z and into the liquid conducting tube X, and any suitable means such as a throttle valve may be provided for controlling the passage of liquid into 75 the machine. The back head plug a is preferably formed with a threaded end portion k which is adapted to be screwed into a recess o formed in the back head J which serves to hold the plug a in position relative to the 80 back head.

The back head plug a is preferably formed with a stem p which lies in the hollow bore of the back head extension R and is in this instance formed with a head q 85 which is provided with a diagonal hole r for the reception of a suitable tool, such as a nail or wire, to enable the back head plug a to be unscrewed from the back head J so that the liquid conducting tube X may be 90 readily removed from the machine. The sleeve W is preferably formed with an extension s having flattened portions t on opposite sides thereof and a pair of lugs u is 95 preferably formed in an upright position on the back head J.

The flattened portions t of the sleeve W are adapted to be inserted between the lugs u as shown in Figure 4 and by applying a 100 suitable tool, such as a wrench, to the stem p or head q of a back head plug a, the back head plug may be separated or removed from the tube X and sleeve W. In this manner the necessity of a special tool or 105 tools for removing the back head plug from the liquid conducting tube is dispensed with and the lugs u serve as a vise for holding the sleeve against rotation while the back head plug is removed therefrom.

110 In the modification shown in Figure 5, the water tube connection is illustrated as applied to a rock drill of the drifter type, in which plug d' is of cylindrical shape and adapted to be screwed into a recess in the back head J of the machine. The liquid 115 conducting tube X is provided with the sleeve W having the tapered portion b and is in other respects like the sleeve W shown in Figure 1. The water enters the tube through the inlet X' and passes through the passage J' in the plug d' to the tube. This modified construction shown in Figure 5 forms a simple unitary device adapted to be 120 applied to standard rock drills.

125 In the further modification shown in Figure 6, which is substantially like Figure 5, the sleeve W' is in the form of a pipe plug, having tapered pipe threads W² which are self tightening when the sleeve is threaded 130 into the plug d'. This pipe plug W' is brazed

or otherwise securely fastened to the water tube X.

Furthermore although the lugs *u* which serve as a vise for holding the sleeve *W* against rotation, are shown formed on the back head of the machine, it is to be understood that they may be formed on any other part of the machine.

I claim:

- 10 1. In a rock drill, the combination with
a back head having a recess and a passage
communicating with said recess into which
liquid under pressure is adapted to be intro-
duced, a member screwed into said recess
15 and having a tapered portion adapted to
cooperate with a tapered seat in said recess
to create a fluid tight connection between
said member and back head, said member
being formed with a recess adapted to com-
20 municate with the passage in said back
head, a liquid conducting tube extending
into said recess, and a sleeve carried by said
tube and adapted to be screwed into the
25 recess in said member, said sleeve being
formed with a tapered portion adapted to
cooperate with a tapered seat in said mem-
ber for creating a fluid tight connection
between said sleeve and member.

2. In a rock drill, the combination of a
30 back head having a recess and a passage
communicating with said recess into which
liquid under pressure is adapted to be intro-
duced, a back head plug adapted to be
screwed into the recess in said back head
35 and having a tapered portion adapted to
cooperate with a tapered seat in said recess
to form a fluid tight connection between
said plug and back head, said plug being
formed with a recess communicating with
40 the passage in said back head, a liquid con-
ducting tube adapted to extend into the
recess in said plug, and a sleeve carried by
said tube adapted to be screwed into said
45 plug, said sleeve being formed with a ta-
pered portion adapted to cooperate with a
tapered seat in said plug for forming a fluid
tight connection between said sleeve and
plug.

50 3. In a rock drill, the combination of a
back head having a recess and a passage
communicating with said recess through
which liquid under pressure is adapted to
be forced, a member removably secured in
55 said recess and having a tapered portion
adapted to cooperate with a tapered seat
in said recess to form a fluid tight connec-
tion between said back head and member,
said member being formed with a recess
60 adapted to communicate with the passage
in said back head the inner end of said re-
cess being tapered, a liquid conducting tube
extending into said recess, a sleeve, having
a threaded portion and a tapered portion
65 carried by said tube removably secured in
the recess in said member adapted to create
communicating with said recess into which
liquid under pressure is adapted to be in-
75 introduced, a back head plug adapted to be
screwed into the recess in said back head and
having a tapered portion adapted to coop-
erate with a tapered seat in said recess to
form a fluid tight connection between said
80 plug and back head, said plug being formed
with a recess communicating with the pas-
sage in said back head, a liquid conducting
tube adapted to extend into the recess in said
85 plug, a sleeve carried by said tube adapted
to be screwed into said plug, said sleeve
being formed with a tapered portion adapt-
ed to cooperate with a tapered seat in said
90 plug for forming a fluid tight connection be-
tween said sleeve and plug, and a stem car-
ried by said plug adapted to enable said
plug, tube and sleeve to be removed from
95 said back head as a unit.

5. In a rock drill, the combination of a
back head having a passage into which liq-
uid is adapted to be introduced, a back head
plug removably secured to said back head and
having a recess adapted to communicate with
100 said passage, the inner end of said recess
being tapered, a liquid conducting tube, a
tapered sleeve having a threaded portion
carried by said tube for removably securing
said tube in said plug the tapered portions
105 of the sleeve and the recess in the plug coop-
erating to form a seal and means on said
sleeve to enable said sleeve and tube to be
removed from said plug.

6. In a rock drill, the combination of a
back head having a recess and a passage
communicating with said recess into which liq-
uid is adapted to be introduced, a back head
plug having a recess communicating with
110 said passage and adapted to be screwed into
said back head, said plug being formed with
a tapered portion adapted to cooperate with
a tapered seat in said back head for form-
ing a fluid tight connection between said
115 plug and back head, a liquid conducting tube
adapted to extend into the recess in said
plug, a sleeve carried by said tube and adapt-
ed to be screwed into said plug, said sleeve
being formed with a tapered portion adapt-
120 ed to cooperate with a tapered seat in said
plug for forming a fluid tight connection
between said sleeve and plug, and means on
said sleeve for enabling said sleeve to be sep-
arated from said plug.

7. In a rock drill, the combination of a
back head having a recess and a passage
communicating with said recess into which
125

liquid is adapted to be introduced, a back head plug having a recess communicating with said passage and adapted to be screwed into the recess in said back head, said plug being formed with a tapered portion adapted to cooperate with a tapered seat in said back head for forming a fluid tight connection between said plug and back head, a liquid conducting tube adapted to extend into the recess in said plug, a sleeve carried by said tube and adapted to be screwed into the recess in said plug, said sleeve being formed with a tapered portion adapted to cooperate with a tapered seat in said plug for forming a fluid tight connection between said sleeve and plug, and flattened portions formed on said sleeve to enable said sleeve to be separated from said plug.

8. In a rock drill, the combination of a back head having a recess and a passage in communication with said recess into which liquid under pressure is adapted to be introduced, a back head plug having a recess adapted to communicate with said passage

and also adapted to be screwed into the recess in said back head, said plug being formed with a tapered portion adapted to cooperate with a tapered seat in said back head to form a fluid tight connection between said plug and back head, a liquid conducting tube adapted to extend into the recess in said plug, a sleeve secured to said tube and adapted to be screwed into the recess in said plug, said sleeve being formed with a tapered portion adapted to cooperate with a tapered seat in said plug to form a fluid tight connection between said plug and sleeve, a stem carried by said plug and provided with a hole adapted to receive a suitable tool for enabling said plug, sleeve and tube to be removed from said back head, and flattened portions on opposite sides of a portion of said sleeve, to enable said tube and sleeve to be separated from said plug.

In testimony whereof I have signed this specification.

WILLIAM PRELLWITZ.
